(57) **CLAIM**

The ornamental design for a set top box, as shown and described.

DESCRIPTION

FIG. 1 is a perspective view of the design;

FIG. 2 is a front view of the design;

FIG. 3 is a rear view of the design;

FIG. 4 is a left-side view of the design;

FIG. 5 is a right-side view of the design;

FIG. 6 is a top plan view of the design;

FIG. 7 is a bottom plan view of the design; and,

FIG. 8 is a perspective view of the design from a different angle.

The broken lines in the Figures show environment for illustrative purposes only and form no part of the claim design.

The Figures include surface shading that represents contour not surface ornamentation.
